(57) **CLAIM**

The ornamental design for a gun safe, as shown and described.

DESCRIPTION

FIG. 1 is a front elevation view of a gun safe showing my new design.

FIG. 2 is a right side, front perspective view of the gun safe of FIG. 1.

FIG. 3 is a right side elevation view of the gun safe of FIG. 1.

FIG. 4 is a rear side elevation view of the gun safe of FIG. 1.

FIG. 5 is a left side elevation view of the gun safe of FIG. 1.

FIG. 6 is a top, front, and right side perspective view of the gun safe of FIG. 1.

FIG. 7 is a top plan view of the gun safe of FIG. 1.

FIG. 8 is a bottom plan view of the gun safe of FIG. 1.

FIG. 9 is a front elevation view of the gun safe of FIG. 1 in an inverted position.

FIG. 10 is a right side elevation view of the gun safe of FIG. 9.

FIG. 11 is a rear side elevation view of the gun safe of FIG. 9.

FIG. 12 is a left side elevation view of the gun safe of FIG. 9.

FIG. 13 is a left side, front perspective view of the gun safe of FIG. 9.

FIG. 14 is a top, front, and left side perspective view of the gun safe of FIG. 9.

FIG. 15 is a top plan view of the gun safe of FIG. 9; and,

FIG. 16 is a bottom plan view of the gun safe of FIG. 9.

The broken lines showing a circular lock in FIGS. 1-16 form

no part of the claimed design.

1 Claim, 4 Drawing Sheets
